UNITED STATES PATENT OFFICE.

LEO HINZ, OF PERTH AMBOY, NEW JERSEY, ASSIGNOR OF ONE-HALF TO FRIEDRICK MARTIN, OF NEW YORK, N. Y.

DESIGN FOR AN AEROPLANE-BODY.

58,233.

Specification for Design. Patented June 28, 1921.

Application filed September 22, 1919. Serial No. 325,561. Term of patent 7 years.

To all whom it may concern:

Be it known that I, LEO HINZ, citizen of Germany, residing at Perth Amboy, New Jersey, have invented a new, original, and ornamental Design for Aeroplane-Bodies, of which the following is a specification.

The design is illustrated in the accompanying drawings in which Figure 1 is a perspective view of the body thereof, showing our new design, and Fig. 2 is a plan view thereof.

I claim:

The ornamental design of an aeroplane body as shown.

In testimony whereof I, LEO HINZ, have signed my name to this specification this 10th day of Sept., 1919.

LEO HINZ.

Witness:

Wm. T. JONES.
